UNITED STATES PATENT OFFICE.

GEORGE W. MARSH, OF OAKLAND, CALIFORNIA.

AUTOMATIC AIR-BRAKE.

SPECIFICATION forming part of Letters Patent No. 396,284, dated January 15, 1889.

Application filed August 1, 1888. Serial No. 281,708. (No model.)

To all whom it may concern:

Be it known that I, GEORGE W. MARSH, of the city of Oakland, Alameda county, State of California, have invented an Improvement in 5 Automatic Air-Brakes; and I hereby declare the following to be a full, clear, and exact description of the same.

My invention relates to an improvement in that class of air-brakes for cars usually known 10 as the "Westinghouse automatic."

My invention consists, in connection with the piston-valve and the sliding valve carried thereby, of a spring arranged to throw the valves back when the pressure within the 15 auxiliary reservoir equals that in front of the piston-valve and of an exhaust-port which is opened by the slide-valve when thus thrown back, so that the brakes shall be relieved only after the auxiliary reservoir shall have been 20 supplied.

In order to understand my improvement and its object, it will be necessary for me to describe particularly and in detail the present construction and operation of the West- 25 inghouse automatic air-brake.

Referring to the accompanying drawings for a more complete explanation of my invention, Figure 1 is a view showing the brake-cylinder in section and the auxiliary reservoir 30 and valve-chest in elevation. Fig. 2 is a vertical section of valve-chest and reservoir. Fig. 3 is an enlarged view of same, showing the parts in position so that the auxiliary reservoir is receiving air, the brakes being not yet 35 relieved, as the exhaust-port c' is cut off by cock L of Fig. 4. Fig. 4 is a horizontal section of same on line xx , Fig. 3. Fig. 5 is a vertical section similar to Fig. 3, the parts being in 40 position to relieve the brake by the exhaust of air through my new port c^2 . Fig. 6 is a horizontal section of same on line yy , Fig. 5. Fig. 7 is a view of the under side of the slide-valve E.

A is the auxiliary reservoir, and B is the 45 brake-cylinder.

C is the valve chest or chamber secured to the front of the auxiliary reservoir.

D is the piston-valve within said chamber, and E is the slide-valve carried by the stem 50 of the said piston-valve.

F is the rotary release or cut-out valve, having a port, f , communicating at one end with the passage a through the auxiliary reservoir, and which leads to the brake-cylinder. The rotary valve F has also port f' , which 55 communicates with the train-pipe G and with the passage H, leading in front of the piston-valve. In the valve chest or chamber C is made a port, c , and an exhaust-port, c' . The port c communicates with the port f of the 60 rotary valve F, and also with the port e of the slide-valve E, which said port e is of an elongated shape and is adapted to join ports c and c' of the valve-chamber. In the forward ring or packing-seat of the valve-chamber is 65 made a groove, I, which communicates with a groove, i , made on the face of the piston-valve, whereby an inlet is afforded for the air into the auxiliary reservoir.

The operation of the device thus briefly 70 described is as follows: It will be understood that, this being an automatic air-brake, the brakes are set up against the wheels by the air in the brake-cylinder and are relieved by the escape of said air, which escape is due to 75 mechanism operated by forcing air into the train-pipe. The air in the train-pipe passes in through the port f' of the rotary valve F and through the passage H, and, entering before the piston-valve D, forces said valve to 80 its seat. This movement of the valve carries the slide-valve E with it, causing its port e to join the ports c c' of the valve-chest, so that the air in the brake-cylinder escapes from 85 said cylinder through the passage a , through the port f of the rotary valve F, through the port c of the valve-chest, port e of the slide-valve, and exhaust-port c' of the valve-chest, thus exhausting and relieving the pressure in 90 the brake-cylinder, so that the brakes are at once relieved.

When the pressure in the train-pipe is relieved, the air in the auxiliary reservoir A forces the piston-valve D backward, which carries the slide-valve with it and cuts off the 95 exhaust c' , bringing another port, e' , which is in said slide-valve, into communication with the port c of the valve-chest, so that the air from said reservoir passes through said ports and through port f and passage a into the 100

brake-cylinder, whereby the brakes are again applied.

The air is supplied to the auxiliary reservoir when the pressure is applied in the train-pipe 5 to relieve the brakes, as described, said air passing through the train-pipe into the space in front of the piston-valve to force said valve to its seat, a portion of the air passing through the grooves I and i in the packing-seat and in the 10 face of the valve D into the auxiliary reservoir.

This is briefly the construction and mode of operation of the present automatic air-brake.

15 The grooves I and i , by which the auxiliary reservoir A is supplied with air, have necessarily to be small, so as to avoid too great an expenditure of the pressure in the train-pipe, which has to do its work upon a great number 20 of valves throughout the train, and therefore but a small portion of air can be taken to supply the auxiliary reservoir. As a consequence, the brakes are relieved before the auxiliary reservoir is supplied, and if it be 25 required to set the brakes again instantly, by relieving the air in the train-pipe, it is obvious that the auxiliary reservoir, being only partially supplied, can only partially apply the brakes. On grades, therefore, there is 30 sufficient time for the car to get started and run away before the auxiliary reservoir is sufficiently supplied with air to apply the brakes. It is the object of my improvement to fully supply the auxiliary reservoir before 35 allowing the brakes to be relieved, so that if it be necessary to instantly apply them there will be sufficient pressure of air in the reservoir to accomplish this.

In the valve-chest C , I make a supplementary exhaust-port, c^2 , which in this instance is 40 just to one side of and between the ports c and c' , and by an offset, e^2 , in the valve E , and which communicates with the port e in said valve, I provide for the communication with 45 the supplementary port c^2 at the proper time. The port e is made of the shape shown either originally or by placing in the valves now in use the block e^3 , which cuts off port c^2 when the slide-valve is forward.

50 To the inner end of the valve-chest is screwed a cap, J , in which is fitted a spring, j , and the stem k of the inner valve, K , the forward end of which presses against the inner end of the slide-valve E , its face fitting 55 against the face-plate d' of the inner end of the stem d of the piston-valve D . The spring tends to force the piston-valve D forward away from its seat. On the outside of the valve-chest I secure a petcock, L , by which I 60 can cut off the regular exhaust-port c' . Now, supposing this exhaust-port to be cut off by the petcock and the pressure applied in the train-pipe, the first effect of this pressure is to force the piston-valve D to its seat, as before; but by reason of the exhaust-port c' being cut off by the petcock the air from the 65 brake-cylinder is not allowed to exhaust

through said port, as it does at present, nor can it exhaust through the new port c^2 , for the block e^3 in the port e of the slide-valve 70 covers said new exhaust-port while the piston-valve is at its seat. The air therefore first passes through the grooves I and i , heretofore described, into the auxiliary reservoir. As soon as the pressure in this reservoir equals 75 the pressure in front of the piston-valve, the spring j throws said valve and the slide-valve E forward. This forward movement of the valve E brings the offset e^2 of the port e of the slide-valve into communication with 80 the supplementary exhaust-port c^2 in the valve-chest, whereupon the air from the brake-cylinder exhausts through said port and the brakes are relieved, as before; but it will be seen that this is not done until the auxiliary 85 reservoir is supplied. The inner valve, K , when the spring j throws it forward, as just described, comes to a seat on the inner end of the valve-chest, so that the air can continue to pass into the auxiliary reservoir 90 only through the small groove d^2 in the face-plate d' on the inner end of the stem d of the valve and through port k' in the inner valve and port, j' , of the cap J . Provision is thus made for avoiding an expenditure of too great 95 a proportion of the air in the train-pipe, which would otherwise pass too freely into the auxiliary reservoir.

This improvement need only be used on grades, as it is there only that the necessity 100 arises for applying the brakes again before the auxiliary reservoir can be supplied. On a level the regular exhaust-port c' can be used by opening the petcock L .

Having thus described my invention, what I 105 claim as new, and desire to secure by Letters Patent, is—

1. In the automatic air-brake herein described, having the auxiliary reservoir, the brake-cylinder, the train-pipe connection, 110 and the valve chest or chamber, with its grooved piston-valve, ported slide-valve, and port c , the spring j , for throwing the valves back when the pressure within the auxiliary reservoir equals the pressure in front of the 115 piston-valve, and the exhaust-port c^2 in the valve-chest, which is opened by the ported slide-valve when thrown back, substantially as and for the purpose herein described.

2. In the automatic air-brake herein 120 described, having the auxiliary reservoir, the brake-cylinder, the train-pipe connection, and the valve chest or chamber, with its grooved piston-valve, ported slide-valve, and port c , the ported inner valve bearing against 125 the inner end of the slide-valve and the grooved inner end of the stem of the piston-valve, the spring acting against said inner valve for causing it to move forward to its seat and throw the piston-valve and slide-valve back when the pressure within the auxiliary reservoir equals the pressure in front of the piston-valve, and the exhaust-port c^2 in the valve-chest, which is opened by the 130

ported slide-valve when thrown back, substantially as herein described.

3. In the automatic air-brake herein described, having the auxiliary reservoir, the 5 brake-cylinder, the train-pipe connection, and the valve chest or chamber, with its grooved piston-valve, ported slide-valve, and port c , the ported cap on the inner end of the valve-chest, the ported inner valve within said 10 cap and bearing against the end of the slide-valve and the grooved inner end of the stem of the piston-valve, the spring within the cap and acting against the inner valve for causing it to move forward to its seat and throw 15 the piston-valve and slide-valve back when the pressure within the auxiliary reservoir equals the pressure in front of the piston-valve, and the exhaust-port c^2 in the valve-chest, which is opened by the ported slide- 20 valve when thrown back, substantially as and for the purpose herein described.

4. In the automatic air-brake herein described, having the auxiliary reservoir, the brake-cylinder, the train-pipe connection, and the valve chest or chamber, with its grooved 25 piston-valve, ported slide-valve, port c , and exhaust-port c' , a cock for closing and opening the exhaust-port c' , a spring for throwing the valves back when the pressure within the auxiliary reservoir equals the pressure in 30 front of the piston-valve, and the supplementary exhaust-port c^2 in the valve-chest, which is opened by the ported slide-valve when thrown back, substantially as herein described. 35

In witness whereof I have hereunto set my hand.

GEORGE W. MARSH.
